TOOL EJECTOR, OR SIMILAR ARTICLE

James A. Scully, Chicago, Ill.

Application July 22, 1955, Serial No. 37,100

Term of patent 14 years

(Cl. D54—13)

FIG. 1.

FIG. 2.

FIG. 3.

FIG. 4.

FIG. 5.

FIG. 6.

Figure 1 is a front elevational view of a tool ejector, or similar article showing my new design;

Figure 2 is a side elevational view thereof;

Figure 3 is a plan view of the same;

Figure 4 is a cross-sectional view taken on the line 4—4 of Figure 1;

Figure 5 is a cross-sectional view taken on the line 5—5 of Figure 1; and

Figure 6 is a cross-sectional view taken on the line 6—6 of Figure 1.

I claim:

The ornamental design for a tool ejector or similar article, as shown.
